UNITED STATES PATENT OFFICE.

AUGUST MERCKENS, OF EAST ORANGE, NEW JERSEY.

VENDING-MACHINE.

No. 811,571.

Specification of Letters Patent.

Patented Feb. 6, 1906.

Application filed February 8, 1905. Serial No. 244,895.

To all whom it may concern:

Be it known that I, AUGUST MERCKENS, a citizen of the United States, residing at East Orange, in the county of Essex and State of New Jersey, have invented an Improvement 5 in Vending-Machines, of which the following is a specification.

My invention relates to vending-machines, and particularly to that class of automatic 10 vending-machines in which a coin of predetermined denomination is inserted through a slot and passes through a coin-tester to such a position in a suitable ejector that through the intervention of the coin a package or other 15 article to be vended is ejected by the operation of the machine.

The object of my invention is the provision of an automatic vending-machine in the operation of which all coins or other devices 20 other than the coin of predetermined denomination intended to operate the machine will be ejected therefrom and also a machine in which if there are no more packages to be vended the coin of predetermined denomination 25 will be returned. My improved vending-machine will therefore not only eject all devices other than the coin intended to operate it, but will also deliver the goods or refund the money to a bona fide vendee.

In carrying out my invention I employ a suitable casing, means operated through the intervention of a coin of predetermined denomination for ejecting the packages to be vended, means for returning the said coin 35 when the machine does not deliver the packages, and means for ejecting from the machine all articles inserted other than the coin of predetermined denomination intended to operate it, all of which will be hereinafter 40 more particularly set forth.

In the drawings, Figure 1 is a section and partial elevation of an automatic vending-machine, illustrating my improvements therein. Fig. 2 is an end elevation of the frame in 45 which the coin-tester is mounted. Fig. 3 is a section on line $z-z$ of Fig. 1 looking toward the rear end of the frame in which the coin-tester is mounted, and Fig. 4 is a front elevation of the plates forming the coin-chute and 50 the parts associated therewith.

a represents the front board of a suitable casing, which may be made in any form adapted to contain the mechanism for operating the machine and the packages to be 55 vended.

b is a frame preferably made of metal and

set in the casing in the requisite position. Within the frame b I employ a coin-tester c , conveniently comprising a fixed plate or member 2, a movable plate or member 3, hinged on a rod 4 and normally maintained in position with its inner face in contact with the lower edge of the fixed plate 2 by means of a spring 5. The lower end of the fixed plate 2 is preferably rounded or provided with a longitudinal groove by which construction a coin-passage is provided between said fixed and movable plates. The outer member of the frame b is provided with a suitable slot c' in alinement with the coin-passage between the fixed and movable plates 2 3, respectively, of the coin-tester. The movable plate 3 is provided with an arm 6, extending from the upper front end of the same, with its lower edge across the upper portion of the slot c' , so that in inserting the coin the movable plate 3 is swung aside by the edge of the coin coming in contact with the lower edge of the arm 6. The movable plate 3 is also provided with an inclined contact-arm extending from the lower forward edge of the same, whose function will be hereinafter set forth. The coin-tester is also preferably provided with a magnet 8, a suitable hinged washer-arrester, and any other devices known to the art for arresting a spurious coin or any other device in the coin-tester.

d represents a gravity-plate which is pivoted at 10 to the inner surface of the frame b in such a position that normally the arm d' of the gravity-plate is clear of the slot 11 in the inner face of the frame b and in alinement with the coin-passage between the fixed and movable plates of the coin-tester, the gravity-plate being held in this position by its arm d'' , which normally rests against the inner end of that portion b' of the fixed plate which passes through the inner portion of the frame b , as indicated in Fig. 2. The gravity-plate d is also provided with a finger d^3 , which preferably projects at right angles therefrom and whose function will also be hereinafter set forth.

e represents a receptacle adapted to contain the packages 12 to be vended, which, as is common in machines of this class, are superimposed in piles within the receptacle e and are maintained in position therein by means of a suitable weight f , also adapted to fit within the receptacle e . The weight f is provided with a projection f' in such a position that when the packages are exhausted

from the receptacle to a sufficient extent the projection f' will contact with the finger d^3 of the gravity-plate d , and thereby cause the arm d' thereof to be swung in front of the slot 11 and across the path of the coin through the coin-tester with its edge against the stop b^2 , as indicated in dotted lines in Fig. 2.

g is a slidable ejector secured to the inner end of a push-rod h , whose outer end passes through the front board a . The ejector g is provided with a slot 13, adapted to receive the coin, and the push-rod h is provided with a sleeve 14, the said ejector g being normally held in position against a stop-bar h' by means of a helical spring 15, bearing at one end against the stop-bar h and at the other end against the sleeve 14, passing within the recessed portion of the same, as indicated, if so desired.

i represents a hopper located directly beneath the opening 11 at the end of the passage in the coin-tester, and 16 is a chute leading from the hopper i to a point directly above the slot 13 in the ejector g and by means of which the coin after passing through the tester is delivered to the ejector g . It will be manifest that in this position the coin itself is employed as the medium by which the lowermost package in the superimposed pile will be ejected upon the push-rod h being moved inward.

k represents a coin-receptacle, and the upper portion 17 thereof is preferably utilized as a slide upon which the ejector g moves. This portion of the coin-receptacle is provided with a slot 18, through which after the lowermost package has been removed from the superimposed pile the coin used in ejecting the same will pass directly through the slot 13 in the ejector g and through the slot 18 into the coin-receptacle k .

l is a hopper situated immediately behind the front board a and directly beneath the coin-tester c . The hopper l communicates with a chute 19, which is in communication with the chute 20, through which the packages to be vended are passed, so that articles passing through either of the chutes 19 20 arrive at the same place and from which they may be obtained. The push-rod h is preferably provided with an arm m , which is secured at one end in the sleeve 14, fixed on said push-rod and extending upwardly beneath the side of the hopper l and provided at its upper end with a rod n , extending parallel with and immediately behind the front board a . The rod n is provided with a pin r , and the relation and position of these parts is such that when the rod h is pushed inwardly the pin r strikes the inclined contact-arm 7, secured to the movable plate 3 of the coin-tester and swings said plate aside.

From the foregoing description it will be seen that I have referred to my improved ap-

paratus in the singular; but it will be manifest that in any given machine the parts may be duplicated at pleasure without departing from the nature and spirit of my invention.

In the operation of the mechanism, assuming that the receptacle e for the packages is filled, the gravity-plate will be in such a position that its arm d' will not interfere with the passage of a coin of predetermined denomination properly inserted through the slot c' in the outer face of the frame b . The coin having passed to its position in the slot 13 of the ejector g , the lowermost package 12 in the superimposed pile of packages will be ejected from the pile by the pressure exerted thereon by the coin in moving the push-rod h inwardly, whereupon the package passes through the chute 20 and the coin drops through the slot 18 into the coin-receptacle. Should, however, the packages be exhausted from the receptacle e , or nearly so, as shown in the drawings, to such an extent that the projection f' , secured in the weight f , contacts with the finger d^3 of the gravity-plate, causing the arm d' thereof to swing to the dotted position shown in Fig. 2 across the path of the coin, the coin will be arrested in the coin-tester in the position shown in Fig. 1, whereupon by moving the rod h inwardly the finger r will strike against the inclined contact-arm 7 and swing the movable plate 3 to the position shown in dotted lines in Fig. 3, whereupon the coin will drop into the hopper l and descend by the chute 19 to that place where otherwise the package to be vended would have been delivered.

It will be evident that the projection f' may be placed in such a position that there may be as many packages remaining in the pile in the receptacle e as may be desired; but in practice the projection f' will be so placed as to cause the coin to be arrested in the coin-tester when the machine shows that the receptacle e is emptied of its packages. It will also be apparent that should it be attempted to operate the machine by means of a spurious coin or other device, which the coin-tester arrests in its passage through the same, all such spurious coins and other devices having been arrested will fall into the hopper l either upon the push-rod h being moved inwardly or upon the insertion of another coin into the machine, and thereby these will also be delivered, by means of the chute 19, at the same place where the packages are delivered when the machine is properly operated.

I claim as my invention—

1. In an automatic vending-machine, the combination with a casing, a package-receptacle and a coin-chute, of devices for retaining a good coin in said chute and operative only when the package-receptacle is empty, a push-rod and means actuated upon operating the push-rod to release the coin from the chute.

2. In an automatic vending-machine, the combination with a casing, a package-receptacle and a coin-chute, of devices for retaining a good coin in said chute and operative only when the package-receptacle is empty, a push-rod, means actuated upon operating the push-rod to release the coin from the chute, and means for refunding the coin.
3. In an automatic vending-machine, the combination with a casing and a receptacle for packages to be vended, of a frame, a plate fixed in said frame in an inclined position, a movable plate hinged adjacent to said fixed plate with an intervening coin-passage, means for retaining a coin between said plates when the receptacle is empty, a push-rod, means actuated upon pushing said rod for liberating the coin from its position between said plates, and means for refunding the coin when so liberated.
4. In an automatic vending-machine, the combination with a casing and a receptacle for packages to be vended, of a frame, a fixed plate mounted in an inclined position within said frame, a movable plate adjacent to said fixed plate with an intervening coin-passage, a gravity-plate pivoted in said frame at the lower end of the said coin-passage, means for closing the coin-passage by said gravity-plate when the package-receptacle is empty, means for liberating the coin from its position within the coin-passage and against the said gravity-plate, and means for refunding the coin when so liberated.
5. In an automatic vending-machine, the combination with a casing and a receptacle for packages to be vended, of a frame, a fixed plate mounted in an inclined position within said frame, a movable plate adjacent to said fixed plate with an intervening coin-passage, a gravity-plate pivoted in said frame at the lower end of the said coin-passage, a weight adapted to fit within the said package-receptacle, a projection on the same adapted to engage the said gravity-plate to swing the same across the said coin-passage when the machine is empty, and means for liberating the coin from its position within the coin-passage and against the said gravity-plate.
6. In an automatic vending-machine, the combination with a casing and a receptacle for packages to be vended, of a frame, a plate fixed in said frame, a movable plate hinged adjacent to said fixed plate with an intervening coin-passage, means for retaining a coin between said plates when the machine is empty, an inclined contact-arm secured to said movable plate, means for moving said movable plate through the intervention of said inclined contact-arm to liberate the coin from the coin-passage, and means for refunding the coin when so liberated.
7. In an automatic vending-machine, the combination with a casing and a receptacle for packages to be vended, of a frame, a plate fixed in said frame, a movable plate hinged adjacent to the said fixed plate with an intervening coin-passage, a push-rod, means for retaining the coin between said plates when the machine is empty, an inclined contact-arm secured to said movable plate, an arm fixed to said push-rod, a rod secured to said arm, a finger fixed in the said rod in such position as to contact with the said inclined contact-arm when the push-rod is moved inwardly, and means for refunding the coin.
8. In an automatic vending-machine, the combination with a casing and a receptacle for packages to be vended, of a frame, a plate fixed in said frame, a movable plate hinged adjacent to the said fixed plate with an intervening coin-passage, a push-rod, means for retaining the coin between said plates when the package-receptacle is empty, an inclined contact-arm secured to the said movable plate, an arm fixed to said push-rod, a rod secured to said arm, a finger fixed in the said rod in such position as to contact with the said inclined contact-arm when the push-rod is moved inwardly, a hopper, and a chute leading therefrom for refunding the coin.

Signed by me this 3d day of February, 1905.

AUGUST MERCKENS.
